CONVEYER STRUCTURE

Robert E. Klein, West Allis, Wis., assignor to
 Chain Belt Company, Milwaukee, Wis., a corporation of Wisconsin

Application September 29, 1941, Serial No. 412,745

5 Claims. (Cl. 198—170)

This invention relates to apparatus for conveying material, and more especially to that type of apparatus in which solid flights are employed with a draft mechanism to propel through a closed conduit material of a freely flowing nature. These solid flights are designed so that during the carrying period of their run, the peripheries of the flights are disposed adjacent the walls of the casing, thereby blocking off longitudinal portions of the material and affording positive means to propel such portions to the discharge outlet of the conveyer.

While these conveyers are normally run at such speeds that the mere provision of an outlet opening appropriately located in the side of the casing will permit gravity discharge of the major portion of the material being handled, even where inclined or vertical runs are encountered, nevertheless it is highly desirable that the top surface of each of the flights be completely cleaned in order that material may not be carried back on the return run of the conveyer.

Efforts have been made to employ flights which are rigidly attached to the draft mechanism, and to so design the top surfaces of the flights as by pitching them at a steep angle, in order that they may shed the material, during vertical runs, at the discharge outlet. Inclined or convex flights of this type, however, have a serious disadvantage in that they tend to crowd the material against the walls of the casing during the carrying runs of the conveyer, and moreover, with some materials, it is practically impossible to pitch the flights steep enough to cause self cleaning, at least without greatly augmenting the crowding effect previously alluded to.

In contra-distinction to these rigidly attached convex or sloping flights, flights have been employed which are pivotally supported by the chain and trippers have been disposed adjacent the discharge outlet to cause tilting of the flights sufficient to clean their respective carrying surfaces. These latter arrangements have the advantage that during the carrying portion of their travel the flights may be disposed at right angles to the path of the draft mechanism, thereby avoiding crowding of materials, whereas in discharging, they may be positively impelled, as by tripping, to cause more complete removal of material.

A highly desirable arrangement of pivoted flights is disclosed in the White Patent 2,271,789 issued February 3, 1942, in that the flights are disposed ahead of the chain attachments and are thus enabled to pivot toward the discharge opening under the impulse of flight tripping means as shown therein. Any method of pivotal attachment, however, which is primarily intended to promote conveying and discharging operations may create difficulties in connection with

the control of the position of the flights after discharge is effected, and during the feeding of new material; and it is to the solution of these difficulties that the present invention is primarily directed.

With these considerations in mind, it is a principal object of this invention to provide an improved conveyer of the solid, pivotal flight type in which friction and wear between the flights and the casing will be prevented during the empty portion of the conveyer's travel, and in which the flights will be positioned prior to receiving material whereby crushing or crowding of the material will be avoided.

Another object of the invention is to provide a conveyer of the character described which will be more efficient in operation than conveyers heretofore employed.

With these objects in view, the invention resides in the novel combination, arrangement and disposition of elements as hereinafter described in detail and pointed out in the appended claims.

For specific embodiments of the invention, reference is made to the accompanying drawing, in which:

Figure 1 is a side elevation of a complete conveyer with part of the casing broken away;

Figure 2 is an enlarged side view of a chain link showing the flight attachment;

Figure 3 is a view of a portion of the link structure shown in Figure 2, looking from the underside of the flight;

Figure 4 is an enlarged side elevation of the tripping device used to position the flights for receiving material;

Figure 5 is a front view of the device shown in Figure 4;

Figure 6 is a side elevation taken partly in section, illustrating the joint between adjacent chain links;

Figure 7 is a section taken on the line 7—7 of Figure 1; and

Figure 8 is a section taken on the line 8—8 of Figure 1.

The conveyer illustrated in the drawing is of the L shaped type, in that the casing has a horizontal portion 11 and a vertical portion 12 through which the draft and scraper mechanism is arranged to run. This particular configuration is by no means the only one which may be utilized in the design of the casing, for the active runs may be entirely horizontal or entirely vertical, or they may be inclined at any desired angle. These various shapes are so well known in the art, that extended elaboration respecting them is not considered necessary.

The L shaped type of conveyer is arranged so that material may be fed through a hopper 13 which communicates with the return or empty run 14 of the conveyer, the hopper being dis-

posed above horizontal portion 11 of the casing. Material which is fed through the hopper is moved by the chain 15 and flights 16 across the top surface of the partition wall 17 which divides the active and return runs in the horizontal portion of the conveyer. Obviously a sliding or pivotal gate may be employed with the hopper opening to control the feed of material, but in most cases this will not be necessary as the solid conveyer flights moving past the opening act as a gate controlling the rate of feed.

The chain and flight construction, shown in greater detail in Figures 2, 6 and 7 is such that the flights 16 when traveling in a vertical direction are at right angles to the plane of the chain links 18. The links which support the flights (in this illustration, alternate links) are provided with forwardly projecting arms 19, each arm having near its forward extremity a transversely arranged aperture for receiving a pin 20 pivotally connecting the flights to the chain. Each flight 16 is shaped so that its periphery is adjacent the walls of the casing when the flight is at right angles to the chain, and in order to straddle the links, the flights have notches 21 as illustrated in Figure 8. The inner end of the flight is supported by a boss 22 on the arm 19, and while resting on this boss, the flight is in a horizontal position during upward travel of the chain through the vertical section of the casing.

The chain construction which is used with the conveyer is preferably of the type described in my copending application for U. S. Letters Patent, Serial Number 407,063, filed August 15, 1941, in which the links 18, when viewed from the front, are Y-shaped; the bifurcated portion 23 at one end being wide enough to accommodate the shank member 24 of the adjacent link in articulating relation thereto. For ease in assembling and disassembling, the shank end of the link is provided with a key shaped aperture having straight portions 25 in registry with the aligned apertures in the legs of the bifurcated portion. Pins 26 have flattened intermediate portions or grooves 27 of approximately the same width as that of the shank end of the link, and when assembled form a dead bearing, with the pins locked against lateral displacement. To remove the pins, adjacent links may be pivoted at right angles and the shank end moved sufficiently so that the pin registers with the circular portion 28 of the key hole slot.

Movement of the pin with relation to the slot, without pivoting in the manner described, is prevented by the abutting relation of the end of the shank portion 24 against the bottom 29 of the legs of the double hinge portion of the adjoining link. Reflex of the chain, i. e., articulation in a direction opposite to that required by sprocket engagement, is prevented by the provision of an approximately square corner 30 on the end of the shank portion 24. A slight amount of reflex is necessary to enable the chain to pass around bends in the casing, such as is provided by the bend 31 on the return run of the conveyer illustrated in Figure 1, and to accomplish this the flat end of shank portion 24 is not at right angles to the link but a slight gap angle is provided between the abutting surfaces when the chain is under tension to permit the desired amount of reflex.

The reason for this rigid back arrangement will now be described; should the chain become disconnected for any reason and collapse in the casing, it is important to prevent reflexing, because if the chain links reflex sufficiently, the pin may

slide back into the circular portion 28 of the key-hole slot and being locked there, it is extremely difficult to remove the chain from the casing. Flexing of the links in the normal direction in that portion of the casing where the flights are closely confined is effectively limited because the link which carries the flight is held against the inner or back wall 32 of the casing by the flight and the rigid arm 19.

10 Discharge of the conveyer is promoted by the provision of a tripping cam 33 disposed adjacent the discharge opening 34, said cam being arranged to lift the back portion of the flights as they travel by and to propel them into an inclined position whereby their top surfaces may be effectively cleaned. Cam 33 as indicated in Figure 7 is arranged to straddle the chain and the working contour of the cam is so designed that after quickly tripping the flight, the flight may 15 be momentarily held in tripped position to insure discharge.

The upper end of the casing is provided with a cover 35 in which is disposed a head sprocket or wheel 36, mounted for rotation by shaft 37, the latter driven by a suitable source of power not shown. The sprocket is preferably designed so that the teeth may engage the bifurcated ends of the links, in which case the sprocket must have a medial groove to permit the links to lie as 20 chords on the sprocket periphery. In order to control the speed of cam 33, a direct drive from shaft 37 may be employed, as indicated by the dotted chain 38, the ratio of speeds of sprocket 36 and cam 33 being such that the cam will engage each flight in proper timed relation to effect 25 tilting as described in the aforesaid White patent.

The partition dividing the two vertical leg portions is bent at a point just above the outlet 34 and then extended over the return leg portion 40 to form an inclined deck 39, down which material may be discharged which is not completely removed after tripping of the flights. As indicated in Figure 1, this deck extends well under the head wheel 36 and is also closely adjacent 45 cam 33, the motion of the latter helping to sweep the material down the deck and into the outlet. The width of the casing defined by the side walls 40 of the head section is also increased 50 adjacent the outlet, thereby facilitating discharge by permitting material to fall off the flights toward the sides.

Accordingly it will be seen that the side walls 40, the deck 39 and the front wall having the opening 34 provide a discharge chamber enclosing the tilting means 33 and communicating with the casing 12 through which the chain travels. Since the side walls 40 slope away from the flights below the deck 39, and above the outlet 34, there is a gradual loosening of material at the sides 60 prior to emergence of the flights above the deflection of the back wall 32 and this material is circulated either onto the space directly above the next subsequent flight or else through the outlet 34, depending on how filled the space between the flights may be and the pressure of the subsequent material moving upwardly. But in either event, the material does not lodge between the flights and the casing and a clean discharge is constantly effected.

70 After the chain passes the head sprocket, gravity causes the flights to swing away from abutment 22, and to limit such swinging motion, the underside of the flight is provided with a stop 75 which is arranged to abut an extension 42 formed on the flight-supporting arm 19. These

stops 41 and 42 are arranged to permit pivoting of the flights to a suitable angle of the order of 45°, which is sufficient for the discharge of material and yet keeps the flights out of contact with the casing while articulating around the sprockets or traveling down the vertical leg. The disposition of this stop on the underside of the flight avoids any interference with the free flow of material off the top of the flight during discharge and also minimizes the possibility of material being pocketed between the link and the flight during the swinging motion of the latter.

Referring again to the feeding portion of the conveyer, provision is made at the end of the horizontal section 11 for an idler sprocket 43, which is spaced from the end of the partition 17 dividing the return and active run a sufficient distance to permit material to flow over the end of the partition into the lower run. Disposed ahead of the area which is occupied by the down flowing material is a tripping device generally designated 44, which has an arm 45 extending into the path of the forwardly tilted flights leaving the idler sprocket 43. This device, enlarged views of which are shown in Figures 4 and 5, may be pivotally mounted in the side of the casing, and a counterweight 46 may be attached to a second arm 47 arranged so that the counterweight may retard the forward leaning edge of the flight until the flight is in vertical position, after which the flight may pass under arm 45, and the weight will then swing the arm back into position for engaging the next flight.

The relation of the positioning device 44 to the partition 17 is such that material moved over the end of the partition by the flights on the upper run may flow into the space between the flights on the lower run without interfering with the positioning device, and the flights may be positioned before any substantial amount of material has a chance to flow over the forward leaning edge into the succeeding flight compartment. This arrangement has been found to be of a distinct advantage because while the weight of material tends to force the flights into a position contiguous to abutment 22 during vertical runs, yet, if substantial amount of material is behind the flight when it is pressed back into this position, the latter material will be crowded together and may even be crushed.

The invention having been described, what is claimed is:

1. In a conveying device, the combination of a casing having a portion disposed mainly horizontal and divided into vertically superimposed conveying conduits; an endless chain and pivotal flights attached thereto arranged to operate through said conduits; a foot sprocket at the terminal of the horizontal conduit; a partition separating the conduits, and a tripping device disposed in the path of the flights traveling through the lower conduit and removed a substantial distance from the foot sprocket, said device being arranged to position the flights leaving the foot sprocket so that they may assume a substantially vertical position immediately prior to receiving material in the horizontal portion of the conveyer's run.

2. In a conveyer having a casing with an upwardly extending, substantially enclosing leg and an outlet and flights pivotally secured thereto for

propelling material through the casing, the combination of a draft mechanism comprising links, each having a bifurcated portion at one end and a shank portion at the other end arranged to extend between the bifurcated portion of an adjacent link and having a keyhole slot therein, a pin connecting the links and having a flat portion cooperating with the key hole slot to provide a dead bearing therewith, the end of the shank portion of the link closely abutting that part of the adjacent link which connects the bifurcated portion, whereby the connection of the links can only be effected by pivoting the adjacent links at substantially right angles to each other, and means on the abutting portion of the links limiting pivotal movement of adjacent links so as to require connection of the links by pivoting in the direction of link articulation only.

3. A conveyer for transporting solid flowable material comprising a casing having an inlet opening and a discharge outlet, an endless chain arranged to move through said casing, a plurality of flights pivotally secured to said chain and disposed when in one position of such pivotal securing to occupy substantially the entire cross section of said casing, means for tilting the flights out of said position when adjacent the discharge outlet to facilitate cleaning of the flights, and means disposed ahead of said inlet opening for 30 tilting the flights into said position prior to their engagement by the material.

4. In a conveyer for transporting solid flowable material in bulk, a casing substantially enclosing the carrying run of the conveyer, said casing having a back wall, side walls and a front wall provided with a discharge outlet, an endless chain arranged to move longitudinally through said casing, a plurality of flights pivotally secured to said chain arranged to occupy substantially the entire cross section of the casing when transverse to the chain, means for tilting said flights serially adjacent said discharge outlet, and a discharge chamber enclosing said tilting means and communicating with said casing comprising extensions of said back and side walls, said extensions each sloping away from said flights to provide for the gradual loosening of material directly above the flights and to remove all lateral support therefor prior to flight engagement by said tilting means.

5. In a conveyer for transporting solid flowable material in bulk, a casing substantially enclosing the carrying run of the conveyer, said casing having a back wall, side walls and a front wall provided with a discharge outlet, an endless chain arranged to move longitudinally through said casing, a plurality of flights pivotally secured to said chain arranged to occupy substantially the entire cross section of the casing when transverse to the chain, means for tilting said flights serially adjacent said discharge outlet, and a discharge chamber enclosing said tilting means and communicating with said casing, said discharge chamber comprising an extension of said back wall inclined away from the path of said flights at a point above said outlet and below said tilting means and extensions of said side walls also sloping away from said flights at points below the deflection of said back wall and above said outlet.
